[57] **CLAIM**

The ornamental design of a slide holder for an immunostaining workstation, as shown and described.

DESCRIPTION

FIG. 1 is a front perspective view of a slide holder for an immunostaining workstation, showing our new design;

FIG. 2 is a rear elevational view thereof;

FIG. 3 is a side elevational view thereof; the opposite side elevational view being identical thereto;

FIG. 4 is an end elevational view thereof; and,

FIG. 5 is an end elevational view thereof, opposite that shown in FIG. 4.

FIG. 1

FIG. 2

FIG. 3

FIG. 5

FIG. 4
